UNITED STATES PATENT OFFICE.

ROBERT S. GOULD, OF EAST ORANGE, NEW JERSEY.

CURTAIN-POLE JOINT.

SPECIFICATION forming part of Letters Patent No. 317,339, dated May 5, 1885.

Application filed January 26, 1885. (No model.)

To all whom it may concern:

Be it known that I, ROBERT S. GOULD, of East Orange, in the county of Essex and State of New Jersey, have invented certain new and 5 useful Improvements in Curtain-Pole Joints, of which the following is a specification.

This invention relates to an improved combination of curtain-pole joint and bracket by which separate brackets for each pole at each 10 side of the joint can be dispensed with and the curtains moved up close to the joint without being interfered with by the brackets.

The invention consists of a spherical curtain-pole joint having a screw-rod passing centrally through the same, said screw-rod being 15 attached to the wall and provided with a sleeve between the wall and the joint, so as to hold the spherical joint in position. The pivot-connection of the curtain-pole is located in 20 the spherical joint and below the screw-rod, so as not to interfere with the latter.

In the accompanying drawings, Figure 1 represents a plan showing my combined curtain-pole joint and bracket. Fig. 2 is a horizontal section of my combined curtain-pole 25 joint and bracket, drawn on a larger scale. Figs. 3 and 4 are vertical sections taken, respectively, on lines *x x* and *y y*, Fig. 2.

Similar letters of reference indicate corresponding parts.

A A in the drawings represent the curtain-poles, which are provided with end caps, *a*, and fixed eye-rods *b*, which latter are screwed into the ends of the curtain-poles A A. The 35 eye-rods *b b* pass through slots *b'* into a spherical shell, B, which is made of two hemispherical shells that are united by a rim-joint. The eye-rods *b* are provided at the interior of the spherical shell B with an S-shaped bend and 40 connected by a pivot, *d*, that is located below the center of the shell B, made of angular shape and soldered at the ends to the inner wall of the shell, as shown in Fig. 4. A bracket-rod, C, passes through the center of the shell B in the same plane with the shanks of 45 the eye-rods *b*, but above the pivot of the same, the front of the bracket-rod C being provided with an ornamental head, C', while the shank is threaded, so as to be screwed into 50 the wood-work of the window-casing. The

ornamental head C' is nicked, so as to facilitate the screwing in of the bracket-rod C by a screw-driver. The distance of the curtain-pole joint from the window-casing is regulated by a tubular sleeve, D, that abuts by its flanged 55 rear end, D', against the window-casing. By using a sleeve and bracket-rod of greater or smaller length the required distance of the joint from the window-casing can be readily obtained.

The advantages of my combined curtain-pole joint and bracket are, first, that the joint is supported in the angle formed by the wood-work, as shown in Fig. 1, without requiring separate brackets, one at each side of the 65 joint; secondly, that the bracket forms a part of the joint, and is furnished with the same; thirdly, that the curtains can be moved up close to the joint, as the separate brackets at each side of the joint heretofore in use are dispensed with.

Having thus described my invention, I claim as new and desire to secure by Letters Patent—

1. The combination, with a curtain-pole joint, of a bracket-rod passing through the 75 joint and a tubular sleeve interposed between the joint and the wood-work of the window-casing, substantially as set forth.

2. The combination, with a curtain-pole joint formed of a spherical shell, of eye-rods 80 attached to the curtain-poles and pivoted to each other at the interior of the shell and a bracket-rod passing through the center of the shell, substantially as set forth.

3. The combination of a curtain-pole joint 85 consisting of a spherical shell, eye-rods attached to the poles and pivoted at the inside below the center of the shell, a bracket-rod passing through the center of the shell and provided with a nicked head and a threaded 90 shank, and a tubular sleeve interposed between the shell and the wood-work, substantially as set forth.

In testimony that I claim the foregoing as my invention I have signed my name in presence of two subscribing witnesses.

ROBT. S. GOULD.
